UNITED STATES PATENT OFFICE.

LUTHER C. CROWELL, OF NEW YORK, N. Y., ASSIGNOR TO ROBERT HOE,
THEODORE H. MEAD, AND CHARLES W. CARPENTER, OF SAME PLACE.

FEEDING MECHANISM.

SPECIFICATION forming part of Letters Patent No. 626,676, dated June 13, 1899.

Application filed July 15, 1898. Serial No. 686,004. (No model.)

To all whom it may concern:

Be it known that I, LUTHER C. CROWELL, a citizen of the United States, residing at New York, county of Kings, and State of New York, have invented certain new and useful Improvements in Feeding Mechanism, fully described and represented in the following specification and the accompanying drawings, forming a part of the same.

10 This invention relates to improvements in feeding mechanism.

In a companion application, serially numbered 682,319 and filed June 2, 1898, are described certain improvements in feeding mechanisms primarily adapted for use in connection with wrapping machinery for wrapping papers, books, pamphlets, magazines, and other similar articles, but also applicable for feeding to various other kinds of machines.

20 The subject-matter of this application relates to certain specific modifications of the subject-matter described and broadly claimed in the application above referred to.

The invention consists in certain constructions, parts, improvements, and combinations to be hereinafter fully described, and more particularly pointed out in the claims hereunto appended.

In the accompanying drawings, which are hereby constituted a part of this application, Figure 1 is a side view of a feeding mechanism embodying the invention, the frame and certain of the operating parts being shown in dotted lines and certain parts being also shown in section. Fig. 2 is a sectional detail of the carriage and some of its connected parts. Fig. 3 is an end view, certain parts being shown in section. Fig. 4 is a plan view, certain parts being shown in section. Figs. 5, 6, 7, and 8 are detail views, on an enlarged scale, illustrating the operation of the devices for removing the sheet, paper, or other article from the stack or pile. Fig. 9 is a detail view showing the rack-bar by which a rotary movement is given to the detaching device.

45 The frame of the machine is indicated at A. The frame is formed to provide ways A', upon which reciprocates a carriage C, which is formed by suitable side bars C² and cross-bars C³, and carries two sets of longitudinal bars

C⁴ C⁵. This carriage is preferably provided with rollers C'. The frame A is provided with standards B, which are connected by cross-bars B'. The standards have adjustably connected to them by means of slots and 55 set-screws or in any other suitable manner supports B², which carry uprights B³. The cross-bars B', before referred to, carry similar uprights B³, the whole forming a frame for retaining the pile or stack of articles in position to be acted upon by the feeding devices. The carriage C, before referred to, reciprocates beneath this pile-retaining frame.

The carriage C is provided with a rack C², which engages with a toothed segment D, 65 mounted upon a rock-arm D', suitably journaled in the frame of the machine. This rock-arm is connected by a rod E to a crank-stud F' on a crank-disk F, mounted on a shaft F², which is also suitably journaled in the frame. 70 The shaft F² is provided with a gear-wheel F³, which meshes with a gear-wheel G' on the main shaft G. The main shaft is rotated by any suitable source of power, and when so rotated it will be seen that the carriage will 75 be reciprocated beneath the pile-retaining frame before described by means of the devices just described.

In the carriage C is journaled a shaft H. 80 This shaft H carries a series of grooved pulleys H' and is provided on one of its ends with a gear-wheel H², which engages a rack H³, (shown in dotted lines in Fig. 1,) mounted on the pile-retaining frame, before described. To each of the grooved pulleys H' is connected 85 one of a series of tapes or bands I, the other end of these tapes or bands being connected to a bar K, which is mounted on the standards B of the pile-retaining frame, the arrangement being such that the tapes pass beneath the pile-retaining frame and between it and the bars C³ C⁴ of the carriage, and therefore act to support the pile of articles contained in the pile-retaining frame. It is obvious that as the carriage reciprocates the 90 shaft H will be revolved by reason of the engagement of the gear H² with the rack H³, and the tapes or bands I will be wound on and unwound from the grooved pulleys, before referred to, and that when they are un- 100

wound they will, as stated above, serve as the support for the pile of papers, pamphlets, books, or other similar articles.

Passing through the grooved pulleys H' is a shaft L , carrying bent hooks L' . This shaft carries at one end a disk M^7 , which is provided with a stop-plate M , having a pair of stops $M' M^2$, (see dotted lines in Fig. 5,) which engage with a suitably-mounted stop-pin M^3 .

10 The stop-plate M is further provided with a pin M^5 , to which is connected a spring M^6 , the other end of the spring being connected to a pin on the disk M^7 , mounted on the shaft H , before referred to. The spring M^6 is so arranged that when the shaft L is rocked by the means hereinafter to be described and the pin M^5 passes the center in either direction the spring will assist in the rocking movement and hold the shaft reliably in position.

15 20 with one of the stops $M' M^2$ against the stop-pin M^3 . The opposite end of the shaft L is provided with a collar N , from which projects a pair of arms $N' N^2$. These arms are staggered or offset, as shown, and engage with suitable projections $O O'$, the projection O being mounted in the frame A of the machine and the projection O' being mounted on the traveling carriage. As the carriage is reciprocated and the shaft H and its connected

25 30 parts rotated, as hereinbefore described, the arms $N' N^2$ will strike the projections $O O'$, before referred to, and the shaft L will be rocked thereby.

Extending across the carriage C near one of its ends is a bar P . On this bar P is mounted a drum R . Within the drum and surrounding the bar is a spring S , one end of which is connected to the bar P and the other end of which is connected to the drum R .

40 The drum R is preferably constructed to form a series of broad-faced pulleys R' , herein shown as three in number; but it is of course obvious that as many of these pulleys may be provided as is deemed necessary or desirable.

45 Upon these pulleys are wound a series of broad tapes or supporting-bands I^2 , one end of each of these bands being connected to each of the pulleys R' , before described, and the other end being connected to a stationary

50 55 bar K^2 , which is mounted in the frame. It is obvious that as the carriage is reciprocated in one direction the broad supporting bands or tapes will be first unwound from the pulleys R' against the tension of the spring and then rewound thereon by the action of the spring as the carriage returns.

Extending across the carriage and mounted therein is a bar T , this bar being located between the grooved pulleys H' and the broad pulleys R . This bar T is provided with a series of bridge-pieces T' , the purpose of which will be hereinafter described.

Beneath the path of the reciprocating carriage is a series of tapes U . These tapes are mounted upon suitable pulleys $U' U^2$, one set of which may be driven in any suitable or desired manner. A second set of tapes U^3 is

also provided, the purpose of which is to carry the paper or other article to the machine to be fed, and any suitable sheet-controlling mechanism—such, for instance, as the ordinary drop-roll mechanism shown in dotted lines in Fig. 1—may be used to coöperate with the tapes U . U^4 indicates any ordinary belt-tightening mechanism.

The construction being as above described, the operation is as follows: Referring to Fig. 1, it will be understood that the carriage has completed its movement toward the left of the observer and is about to reciprocate to the right, thereby removing a sheet from the pile in the pile-retaining frame. Immediately before the carriage completes its movement to the left the arm N^2 has been caused by the rotation of the shaft H , under the influence of the gear H^2 and the rack H^3 , to strike the projection O' , which is mounted in the carriage. This has rocked the shaft L and caused the bent retaining-pins L' , the ends of which are bent toward the pile in the retaining-frame, to take over the edge of the lowest paper or other article in the retaining-frame. The sheet is thereby held at its edge between the pins and the circumference of the grooved pulleys H' . As the carriage starts upon its return movement the sheet, being held at its edge, as before stated, is bent down and carried around by the pulleys H' , which are being rotated by reason of the engagement of the gear H^2 with the rack H^3 . At the same time the supporting-tapes I begin to be wound up on the grooved pulleys, and therefore begin to pass out from under the pile. As the carriage continues its movement to the right the tapes I are progressively withdrawn from under the pile, and at the same time the bridge and guiding pieces T' come under the forward edge of the pile and temporarily support it. The further movement of the carriage causes the supporting-bands I^2 , which have begun to be unwound from the drum R' , to come into position where they also act to support the pile. When the carriage has reached the proper point in its reciprocation and the shaft has reached the proper point in its rotation, the arm N' will be brought in contact with the projection O , mounted on the frame. The shaft L will then be rocked in the direction opposite to that in which it was rocked before, and the bent hooks L' will be withdrawn from the top of the sheet. The sheet will now, however, continue to be fed by the frictional action of the grooved pulleys, before referred to, and as soon as its head reaches the upperstretch of the tapes U it will be carried ahead by these tapes, the several parts assuming the position indicated in Fig. 2. When the carriage has completed its movement to the right, at which time the pile in the rotary frame will be wholly supported by the bands I^2 and the bridge-pieces T' , the sheet will have been entirely detached from the pile and will be fed ahead by the tapes against the stops of the drop-roll mech-

anism, before referred to. At the proper time these stops are withdrawn and the sheet will pass to the tapes U^e and be by them delivered to the wrapping-machine or any other suitable machine. The carriage having finished its reciprocation to the right then starts upon its return. The supporting-bands I^2 will now be rewound upon the drums R' , thus ceasing to act to support the pile of sheets, and the supporting bands or tapes I will be unwound from the grooved pulleys H' and will again support the pile. Just as the carriage is about to complete its movement to the left the rocking of the shaft L is effected in the manner before referred to, and at the instant of the completion of the movement of the carriage in this direction the bent hooks have laid hold of the edge of the next sheet preparatory to causing its removal in the manner hereinbefore described.

While the apparatus described is an effective means for removing sheets from the bottom of a stack or pile, it is obvious that it is not confined to such use. It might, with obvious changes, be used to feed sheets from the top of a pile.

In general, it is to be understood that the invention is not limited in its scope or application to the specific details of construction described in the foregoing specification. Parts of the mechanism embodying the invention may be used independently of other parts, and many changes may be made therein and other constructions substituted without departing from the spirit and scope of the invention.

What is claimed is—

1. In a feeding mechanism, the combination with a pile-retaining device, of a sheet-detaching device reciprocating with respect to the pile, flexible devices for acting on the pile on each side of the sheet-detaching device, said flexible devices being progressively withdrawn from the front of the detaching device and progressively advanced behind it, substantially as described.

2. In a feeding mechanism, the combination with a pile-retaining device, of a sheet-detaching device, means for giving the sheet-detaching device both rotary and reciprocating movements and flexible devices for acting on each side of the sheet-detaching device, said devices being progressively withdrawn from in front of and progressively advanced behind the sheet-detaching device, substantially as described.

3. In a feeding mechanism, the combination with a pile-retaining device, of a carriage reciprocating with respect to the pile-retaining device, a rotating sheet-detaching device carried by the carriage, flexible devices for acting on the pile also carried by the carriage and located on each side of the sheet-detaching device and means for controlling the action of said flexible devices whereby as the detaching device acts to withdraw the sheet the devices for acting on the pile will be re-

spectively advanced behind the pile and withdrawn from in front of it, substantially as described.

4. The combination with a pile-retaining device, of flexible supporting devices located beneath the pile-retaining device and alternately acting to support the pile, and means for removing a sheet from the under side of the pile, substantially as described.

5. The combination with a pile-retaining device, of a pair of flexible pile-supports located beneath the pile-retaining device and alternately acting to support the pile, and rotary means for removing a sheet from the pile, substantially as described.

6. The combination with a pile-retaining device, of a carriage reciprocating beneath the pile-retaining device, rotating sheet-detaching means mounted in the carriage, flexible pile-supporting devices on each side of the sheet-detaching means, and means whereby as the carriage reciprocates each of the pile-supporting devices is alternately caused to support the pile and be withdrawn therefrom, substantially as described.

7. The combination with a suitable frame, of a carriage reciprocating therein, winding devices mounted in the carriage and two sets of tapes or bands, one end of each set being connected to the winding devices and the other end being connected to the frame, whereby as the carriage reciprocates each set of devices will alternately be wound on and unwound from the winding devices, substantially as described.

8. In a feeding mechanism, the combination with a suitable frame, of a pile-retaining device mounted thereon, a carriage reciprocating therein, a sheet-detaching device mounted in the carriage, winding devices also mounted in the carriage on each side of the sheet-detaching device, and two sets of tapes or bands, one end of each set being connected to the winding devices and the other end being connected to the frame of the machine, substantially as described.

9. In a feeding mechanism, the combination with a suitable frame, of a pile-retaining device mounted thereon, a carriage reciprocating therein, a rotary sheet-detaching device mounted in the carriage, winding devices also mounted in the carriage on each side of the rotary sheet-detaching device, and two sets of tapes or bands, one end of each set being connected to the winding devices and the other end being connected to the frame of the machine, substantially as described.

10. In a feeding mechanism, the combination with a suitable frame, of a pile-retaining device mounted thereon, a carriage reciprocating therein, a sheet-detaching device mounted on the carriage, winding devices also mounted on the carriage, two sets of tapes or bands, one end of each set being connected to each of the winding devices and the other being suitably connected to the frame of the machine, a gear and rack for rotating one set of

- winding devices, and a spring for controlling the operation of the other set of winding devices, substantially as described.
11. In a feeding mechanism, the combination with a suitable frame, of a pile-retaining device mounted thereon, a carriage reciprocating therein, a shaft mounted in the carriage, grooved pulleys carried by the shaft, means for rotating the shaft, means acting in conjunction with the grooved pulleys to hold the sheet on the circumference thereof, suitable supporting tapes or bands one end of which is connected to the grooved pulleys, the other end being connected to the frame of the machine whereby, as the carriage is reciprocated, the tapes will be wound and unwound, and means progressively advanced beneath the pile to support it as the tapes are wound on the pulleys, substantially as described.
12. In a feeding mechanism, the combination with a frame, of a pile-retaining device supported thereon, a carriage reciprocating therein, a shaft supported in the carriage, means for rotating the shaft, grooved pulleys mounted on the shaft, a second shaft carrying bent hooks and coöperating with the

grooved pulleys, a set of tapes or bands, one end of which is connected to the grooved pulleys and the other end of which is connected to the frame, a second set of tapes, a winding device, to which one end of the second set of tapes is connected, the other end being connected to the frame, and means for operating the shaft which carries the bent hooks to cause it to lay hold of and release the sheets, substantially as described.

13. In a feeding mechanism, the combination with a pile-retaining device, of a carriage, a rotary sheet-detaching device carried by the carriage, flexible supporting devices located on each side of the sheet-detaching device and caused by the rotation of the carriage to alternately support the pile and suitably-mounted bridge-pieces between the flexible pile-supporting devices, substantially as described.

In testimony whereof I have hereunto set my hand in the presence of two subscribing witnesses.

LUTHER C. CROWELL.
